(57) **CLAIM**

The ornamental design for a socket contact, as shown and described.

DESCRIPTION

FIG. 1 is a top plan view thereof;
FIG. 2 is a front elevation thereof;
FIG. 3 is a bottom plan view thereof;
FIG. 4 is a left-side elevation thereof;
FIG. 5 is a right-side elevation thereof;
FIG. 6 is a downward perspective view thereof; and,
FIG. 7 is an upward perspective view thereof, wherein the subject socket contact is an article that is to be crimped on an electric wire end, before placed and fixed in a connector housing so as to be capable of electrically engaging with a mating connector not shown.

A rear elevation of the socket contact appearing symmetrical with the front elevation thereof is excluded from the drawings.
